UNITED STATES PATENT OFFICE

CLYDE T. CADWALLADER, OF BUFFALO, NEW YORK

DRY CLOSET

Application filed June 11, 1929. Serial No. 370,007.

This invention relates to dry closets, and it is an object of the invention to provide a device of this kind which is highly sanitary and which is particularly adapted for use in rural districts or other places where there is no water under pressure.

Another object of the invention is to provide a closet of this kind which can be conveniently used inside of and on the upper 10 floor or floors of a building and wherein means are provided for the convenient and ready carrying out from the building of excrement and other refuse collected within the box of the closet.

15 The invention consists in the details of construction and in the combination and arrangement of the several parts of my improved dry closet whereby certain important advantages are attained and the device rendered simpler, less expensive and otherwise more convenient and advantageous for use, as will be hereinafter more fully set forth.

The novel features of my invention will 25 hereinafter be definitely claimed.

In order that my invention may be the better understood, I will now proceed to describe the same with reference to the accompanying drawings, wherein:—

30 Figure 1 is a view partly in vertical section and partly in elevation illustrating a dry closet constructed in accordance with an embodiment of my invention;

Figure 2 is a view in top plan of the 35 closet proper as illustrated in Figure 1;

Figure 3 is an elevational view of the paper reel and supporting frame therefor as herein embodied.

As disclosed in the accompanying drawings, 40 1 denotes a slab, preferably of metal and of desired configuration and dimensions, provided with an opening 2 affording communication with a box 3 suitably fastened from below to the under surface of the slab

45 1. Arranged upon the upper surface of the slab 1 and in proper position with respect to the opening 2 is a seat ring 4 of a conventional type.

The slab 1 is maintained at a desired 50 height through the instrumentality of the

supporting legs 5. The legs 5 as well as the walls of the box 3 are preferably of metal.

Carried by the rear portion of the slab 1 is an upstanding frame F, herein disclosed 55 as of a length in excess of the width of the slab 1 and extending beyond opposite sides thereof. This frame F, or more particularly the side vertical members 6 thereof, provide a support for a roll R of water- 60 proof paper, the width of which being in excess of the width of the slab 1, or more particularly the internal width of the box 3.

The top member 7 of the frame F has hingedly connected therewith, as at 8, the 65 arms 9 carried by an elongated knife 10, said knife 10 resting from above upon the paper roll. The knife 10 provides effective and convenient means whereby a desired length of paper may be severed as required. 70

A ring member 11, preferably of metal, is adapted to substantially surround the ring 4 when superimposed upon the slab 1 and the rear portion of this ring member is laterally enlarged in opposite directions, as 75 indicated at 12, to provide a straight bar 14 which is pivotally held to the rear portion of the slab 1 by the clips 15 or the like whereby the ring member 11 may be raised or lowered as required. 80

The portion of the slab 1 rearwardly of the opening 2 and in advance of the bar 14 is provided with an elongated spring pressed clamping plate 16.

In practice, a strip of paper of desired 85 length is severed from the roll R and one end portion of said strip is held to the rear portion of the slab 1 by the clamping plate 16. With the ring member 11 raised the paper strip or sheet is then disposed over the opening 2 whereupon the ring member 11 is lowered. The paper strip or sheet is then pushed downwardly into the box 3 through the opening 2 until it touches the bottom of the box 3 and thereby providing both a container and a seat cover. Upon removal, the ring member 11 is raised and the clamping plate 16 freed from the paper strip or sheet 90 whereupon the corners of the strip or sheet 100

are twisted one about the other as far as practical resulting in a tight package.

The wall W of the room in which my improved closet is arranged is preferably provided with a discharge opening 17 affording communication with the upper end portion of a depending carry-off pipe 18, the lower end portion of which discharges within a portable receptacle 19 of desired configuration and capacity. The upper portion of the carry-off pipe 18 is adapted to be normally closed by a swinging gate 20 and said carry-off pipe below the upper end thereof is provided with a vent opening 21.

15 The package hereinbefore referred to after being taken from the box 3 is passed out through the opening 17 into the upper portion of the carry-off pipe and discharged within the portable receptacle 19. This receptacle 19 can be readily and conveniently moved and dumped as desired.

From the foregoing description it is thought to be obvious that a dry closet constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as herein-after claimed.

I claim:—

1. A dry closet comprising a slab having an opening, a box arranged under the slab and with which the opening communicates, a ring member adapted to engage the slab around the opening, and a paper clamping means associated with the slab and hingedly mounted on said slab, said paper clamping member substantially surrounding said ring member.

2. A closet of the class described comprising a slab, means for clamping a portion of the sheet to the slab, and means for holding marginal portions of a sheet to the slab around the opening, said last named means permitting the sheet to slip when the central portion is forced through the opening into a container arranged beneath the slab.

3. In testimony whereof I hereunto affix my signature.

CLYDE T. CADWALLADER.
